DESIGN FOR A GUIDE FOR AN ELECTRIC IRON CORD

Flora M. Pinska, Oakland, Calif.

Application August 13, 1938, Serial No. 79,302

Term of patent 14 years

To all whom it may concern:

Be it known that I, Flora M. Pinska, a citizen of the United States and a resident of Oakland, in the county of Alameda and State of California, have invented a new, original, and ornamental Design for a Guide for an Electric Iron Cord, of which the following is a specification, reference being had to the accompanying drawing, forming part thereof, wherein

Figure 1 is a perspective side view of a guide for an electric iron cord embodying the design of my invention.

Figure 2 is a plan view of the guide.

Figure 3 is an end elevation of the guide.

I claim:

The ornamental design for a guide for an electric iron cord, substantially as shown.

FLORA M. PINSKA.
